POULTRY DRINKING FOUNTAIN

Filed June 26, 1929

B. J. LIECHTY
INVENTOR

BY *Victor J. Coons*
ATTORNEY

UNITED STATES PATENT OFFICE

BRIGHAM J. LIECHTY, OF SPRINGVILLE, UTAH

POULTRY DRINKING FOUNTAIN

Application filed June 26, 1929. Serial No. 373,864.

This invention relates to a new and improved poultry drinking fountain.

An object of the invention contemplates the provision and arrangement of means whereby live stock will be prevented from entering and contaminating the fountain.

Another object of the invention comprehends an adjustable foot for the fountain whereby the latter may be leveled to insure the passage of water throughout its entire area.

An additional object of the invention embodies means for automatically releasing the water from the reservoir when the latter is disposed in dispensing position.

With the above and other objects in view, the invention further consists of the following novel features and details of construction, to be hereinafter more fully described, illustrated in the accompanying drawings pointed out in the appended claim.

In the drawings:—

Figure 1 is a longitudinal sectional view taken through my invention.

Figure 2 is a top plan view thereof.

Figure 3 is a vertical sectional view taken on line 3—3 of Figure 1.

Figure 4 is a fragmentary elevation of a cap member to support the discharge neck of the reservoir.

Figure 5 is an elevation of a valve member for the reservoir to automatically release the contents of the reservoir when the latter is inverted to occupy a dispensing position as illustrated in Figure 1 of the drawings.

Figure 6 is a bottom plan view of the valve member.

Referring to the drawings in detail where like characters of reference denote corresponding parts, the reference character 10 indicates a cup having a convex bottom 11. The cup is designed to accommodate the neck 12 of a receptacle 13 preferably in the nature of a glass bottle. Spring fingers, such as indicated at 14, are carried within the cup and upon the side wall therefor and sprung against the neck 12 of the receptacle in the manner suggested in Figure 1 of the drawings.

The valve member, as mentioned in the

foregoing, comprises a stem 15, having a valve head 16 of frusto-conical shape upon that end extended within the body portion of the receptacle proper. The tapered side walls of the valve head are designed to engage the inner wall of the neck 12 and to normally seal the latter when the receptacle in its entirety is inverted to prevent spilling of the contents thereof.

A disk member 17, carried upon the opposite end of the stem 15, is provided with a multiplicity of arms 18 projected in diametrically opposed relation tangentially thereof and which extend for greater distances than the bore measurement of the receptacle neck 12 to prevent the valve structure from falling through the neck of the receptacle when the latter is set upright for filling. In actual use, the receptacle 13 is filled in the usual manner and inverted to bring the neck 12 within the cup 10. The disk 17 and arms 18 therefor upon contacting engagement with the adjacent surface of the convex bottom 11 of the cup will elevate the stem 15 and release the valve head 16 from engagement with the neck whereby the contents of the reservoir will be released as between the arms 18 and a discharge opening 19 in the cup.

A drinking trough, indicated generally as 20, and of elongated V-shape formation, is carried by the cup 10 and in communication with a discharge opening 19 therefor. From the foregoing description and accompanying drawings, it is understood that the form of drinking fountain contemplated is of the self-feeding type and the level of the liquid within the trough 20 is fixed or predetermined by the location and height of the convex bottom and the neck 12 of the receptacle and such level will be preserved as long as water remains in the receptacle.

The valve member serves the two fold purpose of acting as a stopper or closure for the discharge neck of the receptacle while disposed in an inverted position and to provide a spacer when arranged in operative position through contact of the arms 18 therefor with the convex bottom 11 to release the contents of the receptacle as same is used up in the trough.

The cup 10 has legs 21 arranged upon the outer side therefor to elevate the latter and the adjacent portion of the trough an appreciable distance from the ground in addition 5 to providing the necessary support for the receptacle. The trough on the other hand is likewise provided with a form of support and due to the fact that the trough may be so constructed as to extend for appreciable distances over uneven surfaces, I provide a foot member 22 upon the outermost end of the trough and which has adjustable connection with an ear 23 thereon. By properly manipulating the adjustable leg 22, the contents of 10 the trough may be maintained at a constant level throughout its length and which will materially aid in the dispensing of the water from the reservoir.

A divider or baffle, such as indicated at 24, 20 and of cross section V-shape, is centrally disposed of the longitudinal axis of the trough immediately above the adjacent meeting portions or apex of the oppositely inclined side walls of the trough. Such disposition is effected through the use and employment of standards 25 having connection with said apex at spaced intervals and which have their uppermost portions projected through openings formed within the baffle or divider. Nut 25 members 26, threadedly adjustable upon the standards 25, are engageable with the bottoms of the portions removed or cut-out portions 30 27 formed within the lowermost edges of the baffle or divider at an appreciable height 35 above the surface and level of the liquid within the trough.

From the Figure 1 illustration, it is noted that the baffle or divider 24 does not extend beneath the shoulder portion of the receptacle but an auxiliary baffle, such as indicated at 28, carried by the adjacent portion of the cup 10, is extended in juxtaposition to the aforementioned extremity of the divider to prevent the live stock from entering the 40 trough and contaminating the contents thereof. The latter instance is especially true in the raising of baby chicks.

The invention is susceptible of various changes in its form, proportions and minor 50 details of construction, and the right is herein reserved to make such changes as properly fall within the scope of the appended claim.

Having thus described the invention, what is claimed is:—

55 A drinking fountain comprising an elongated trough having connection at one end with a cup, a receptacle designed to seat the neck therefor within the bottom of the cup, 60 a valve mechanism included within the neck of the receptacle and engageable with the bottom of the cup to release the contents of the receptacle when the latter has the discharge neck therefor wholly disposed within the cup, 65 and dividers carried by each the trough and

cup to prevent live stock from entering the trough and contaminating the contents thereof.

In testimony whereof I affix my signature.

BRIGHAM J. LIECHTY.
